UNITED STATES PATENT OFFICE.

JOHN A. WELTON, OF CANAL DOVER, OHIO.

APPARATUS FOR FEEDING FINE FUEL.

1,022,805.

Specification of Letters Patent. Patented Apr. 9, 1912.

Application filed May 29, 1911. Serial No. 630,693.

To all whom it may concern:

Be it known that I, JOHN A. WELTON, a citizen of the United States, residing at Canal Dover, county of Tuscarawas, and State of Ohio, have invented certain new and useful Improvements in Apparatus for Feeding Fine Fuel, of which the following is such a full, clear, and exact description as will enable others skilled in the art to which it pertains to make and use the same, reference being had to the accompanying drawings, forming part of this specification.

My invention relates to certain new and useful improvements in apparatus for feeding pulverized fuel into the fire-box of a steam boiler or furnace under pressure, said fire-box having built into it an arch of brick or other refractory material, and said arch being hollow to form a flue or passage adapted to heat air as it passes into the fire-box from a fan casing connected to the arch whereby the heated air is utilized to support and aid combustion.

An object of the present invention is to enable me, if necessary, to do away entirely with the grate-bars in common use, and to make it possible to blow up a pilot fire on the top of a twyer at will to heat up the arch and prepare for the introduction of coal dust and air to be burned in suspension from a pilot fire of coarse coal.

It is, further, an object of the present invention to inject coal dust and air into the fire-box through tubes expanded in the door sheet for that purpose, the same being surrounded with water for the purpose of keeping the tubes cool.

I also propose to control the direction and volume of the flow of air either through the arch to be heated or through the twyer to blow up the pilot fire, or to both places at once if desired; it is this ability to control absolutely the heated air that makes it possible to produce an economical and smokeless fire in the rear of the arch.

I also propose to arrange the exhaust from a steam turbine which is used in my invention so that the exhaust will be composed in the hollow arch and burned. It is the new and novel arrangement of the arch walls in combination with the lining,

the twyer and the manner of introducing coal dust through the end wall of the fire-box door sheet, and the decomposition and burning of the exhaust steam from the turbine, and blowing air through the hollow arch and heating and delivering it to the fire-box of the boiler under damper control that produces my new and useful results.

By the employment of the pilot fire the fireman is enabled to maintain the fire by hand-firing, while the coal damper in the hopper is closed. In fire-boxes that are stay-bolted, or in fire-boxes of small diameter it may not be necessary to insulate against the heat. Under conditions where it is not found to be advantageous the exhaust may be discharged up the stack.

With the above and other objects in view my invention consists of the parts, and the constructions and arrangements and combinations of parts which I will hereinafter describe and claim.

In the accompanying drawings forming part of this specification and in which similar reference characters indicate like parts in the several views, Figure 1 is a longitudinal sectional view of a corrugated fire-box, locomotive type boiler embodying my invention. Fig. 2 is a cross sectional view on the line X—X of Fig. 1 showing parts broken away.

In said drawings, 2, represents a corrugated fire-box of any suitable type within which is constructed an arch, A, which declines downwardly toward the rear end and forms a rearwardly converging chamber into which the fine fuel is discharged, said arch being constructed with an internal flue or passage, 3, through which air may be passed and heated so as to be delivered in the upper front portion of the fire-box there to mingle with the products of combustion passing over the upper front end of the arch. Piercing the outer shell of the furnace and the corrugated wall of the fire-box and suitably expanded in place, are the tubes, 4, 4', which tubes connect with the discharge pipe of the rotary fan or blower, E, said discharge pipe of the fan casing being provided with damper, 5, having a rod by which it may be operated to wholly or partially close the passage through which the

air passes from the blower. It will be understood that this damper may be placed at any point between the fan or blower and the corrugated wall of the fire-box, it only being necessary that it should be so placed as to control the passage of air through the tubes, 4. A similar damper controls the passage of air through the tube, 4'. The fan casing has its discharge pipe, 7, connecting with the tubes, 4, 4' as shown in Fig. 2 and the latter tube, 4', connects with a twyer 42, which is horizontally placed in the lower portion of the fire-box beneath the hollow arch and discharges upwardly to blow a pilot fire of coarse coal and to assist in maintaining the fine fuel in suspension while being burned, said twyer extending from the rear end of the arch outwardly through the front of the fire-box and the wall of the fire-box casing, and having its outer end provided with a cap or closure, 13, which when opened permits the twyer, 42, to be cleaned of fine ashes or other contained foreign material. It will thus be seen that I depend upon the cross or adverse currents of air in the fire-box, one being injected with the fuel and the other being delivered upwardly from the twyer, the air current from the latter blowing across the current of air and fine fuel coming from the dust fan, whereby the fuel is maintained in a state of suspension while being burned.

C represents a steam turbine of any suitable character to which leads a steam inlet pipe, 8, suitably connected with a pressure regulator, 25, contained in the steam space of the boiler and actuated by variations in boiler pressure, substantially as shown and described in my former Patent No. 993,928, dated May 30/11. The steam turbine is also provided with a pipe, 9, through which the exhaust is conducted to the hollow arch to be decomposed and burned. The turbine has a suitable case, 10, and the rotary fan or blower has an appropriate case, 11, while the fire-box is fashioned with an appropriate fire door opening, 12.

Suitable tubes, 14, fixed to a head corresponding to the one shown in Fig. 2, of my aforesaid prior patent, are expanded through the door sheet and have their inner ends positioned for injecting fine fuel charged with air into the fire-box and into the space below the arch thereof and under which arch the fuel is burned in suspension. The fuel is delivered from a suitable fan or blower, F, which fan is shown in Fig. 1 as including a casing having a discharge pipe, 15, connecting with the tubes, 14; the fan has suitable blades, 18, which deliver the fine fuel under pressure through the discharge pipe, 15, one side of the fan casing being open and communicating with a cylinder, 17, in which operate muller wheels or

other pulverizing agents, 16, each of which is designed to operate within a chamber or cell substantially in the manner and for the purpose indicated in my aforesaid prior patent.

The fan, F, and the rotary blower, F, and also the steam turbine, C, if desired, are mounted upon a shaft, 41, which passes through a bearing, 20, and thence through the cylinder, 17, containing the pulverizing agent, as the muller wheel, 16, the opposite end or portion of the shaft, 41, being mounted in any suitable and well known manner; when operated the fan blades, 18, force the pulverized fuel through the discharge, 15, and the tubes, 14, into the fire-box above the twyer, 42, as before described; and air from the rotary blower is delivered through the pipe, 4', into the twyer, 42, for purposes stated, it being understood that the fan for feeding the fine fuel, as also the rotary blower, may be provided with such accessories as are usually found in machines of this character.

By reference to Fig. 1, it will be seen that the corrugated fire-box is provided with a lining, 21, composed of fire-brick or other refractory insulating material, which is designed for the purpose of insulating the fire-box from the injurious action of the extreme heat, said fire-box being inclosed by the shell or casing, 22, having the usual head, 23. The inner end of the corrugated fire-box is also provided with a head, 24, forming a flue sheet and said fire-box will be provided with a suitable outlet for the products of combustion. The pressure regulator, 25, is designed to automatically control the speed of the turbine, C, according to the variations of the boiler pressure, and it acts to increase the revolution of the turbine as the pressure drops below a predetermined point. At the point, 26, will be located a suitable throttle which will enable the fireman to manually vary the speed of the turbine independently of the regulator to take care of a temporary overload.

27 represents the steam dome of the boiler, and 28 is a suitable hanger for carrying or mounting the turbine. The rear end of the fire-box is also provided with a suitable man-hole, 29, to give access to the interior of the fire-box for repairing the tube sheet or other parts and the front end of the fire-box has a fire-brick lining, 30.

By reference to Fig. 2 it will be seen that the damper, 5, controls the amount of air delivered to the hollow arch, and the damper, 5, controls the air delivered through the tube, 4', to the twyer, 42, which twyer is provided with numerous perforations.

The upper front end of the flue or passage in the arch is partially closed by bricks, a, having openings adapted to distribute the air across the entire width of the fire-box, while slanting sides are provided in the fire-

box by means of large specially designed brick as shown at 38, upon which rests the hollow arch in such manner that there is formed a V-shaped receptacle or chamber 5 in which is built a pilot fire.

It will be understood that the fan case, E, may be suspended by suitable brackets, 39, 40, and that the shaft, 41, may be operated by the steam turbine or by any other form 10 of motor, either electric, or internal combustion or otherwise, such motor being designed to furnish the motive power to blow the fires and crush and pulverize and deliver under pressure the fine fuel according 15 of the variations of the boiler pressure. It will be further understood that the twyer, 42, is in the present instance substituted for the grate bars of the former patent but the twyer can be successfully used with grate 20 bars, if desired, without departing from the spirit of the invention.

Having thus described my invention what I claim as new and desire to secure by Letters Patent is:—

25 1. In a mechanism for feeding fine fuel, the combination with a fire-box, of an arch within the same having a flue or passage extending through it, a twyer in the lower part of the fire-box below said arch and dis- 30 charging upwardly and adapted to blow a pilot fire of coarse coal and to maintain the fine fuel in suspension while being burned, an air blower connecting with the twyer, and fuel feeding elements adapted to inject fine fuel and air into the space between the twyer and the arch.

35 2. In a fuel feeding mechanism, the combination with a fire-box or furnace, of an arch within the furnace and extending up- 40 wardly from the rear toward the front end, said arch having an air flue or passage through it, an upwardly directing twyer in the lower part of the furnace below said arch acting to maintain the fuel in suspen- 45 sion while being burned, means for feeding air under pressure to the twyer and to the passage through the arch, valves between the air feeding means and said twyer and arch whereby the admission of air to the 50 twyer and arch may be regulated, and means for feeding fine fuel into the space between the twyers and arch whereby the fuel is burned in suspension under the arch.

55 3. In a mechanism for feeding fine fuel, the combination with a fire-box, of an arch built therein and inclining upwardly from the rear toward the front end, an upwardly directing twyer in the lower part of the fire- 60 box below the arch acting to maintain the fuel in suspension while being burned, means for admitting air under pressure to the twyer, said arch having a flue or passage through it opening into the fire-box near the upper front end, means for admitting air to said passage, means for controlling the ad-

mission of air to the twyer, and passage in the arch, and means for injecting fine fuel and air through the front end of the fire- 70 box whereby the fuel is burned in suspension under the arch, said twyer adapted to blow a pilot fire of coarse coal over which fire the injected fine fuel is burned.

4. In a mechanism for feeding fine fuel the combination with a fire-box, of an arch built therein and inclining upwardly from 75 the rear toward the front end, an upwardly directing twyer in the lower part of the fire-box below the arch acting to maintain the fuel in suspension while being burned, means for admitting air under pressure to the twyer, said arch having a flue or passage through it opening into the fire-box near the upper front end, means for admitting air to said passage, means for controlling the admission of air to the twyer and passage in the arch, and means for injecting fine fuel and air through the front end of the fire- 80 box whereby the fuel is burned in suspension under the arch, said twyer adapted to blow a pilot fire of coarse coal over which fire the injected fine fuel is burned, said fire-box having an internal lining of refractory material.

5. The combination with a fire-box, of an arch built within the same and inclining upwardly from the rear to the front end said arch having an air passage through it opening into the upper front end of the fire-box, of an upwardly directing twyer extending along the lower portion of the fire-box below the arch and piercing the front end of the fire-box, and having a closure for the outer end affording access to the interior of the twyer, and means for supplying air under pressure to the twyer, said twyer discharging upwardly and adapted to blow a pilot fire of coarse fuel and maintain fine fuel in suspension while being burned, and means for feeding fine fuel above the twyer and into the space between said twyer and arch whereby the fuel is burned in suspension under the arch and the products of combustion are mixed with air delivered through the arch near the upper front end of the same.

6. In a mechanism for feeding fine fuel, the combination with a fire-box, and a surface upon which a bed of fuel may be sustained, of an arch within the fire-box extending upwardly and forwardly from the rear end, fuel feeding means delivering fine fuel into the space between said arch and the surface for sustaining the bed of fuel, and means for directing an air current upwardly into the path of the fine fuel whereby the fine fuel is burned in suspension in said space under the arch.

7. The combination of a fire-box having an arch with a flue or passage through it, a twyer in the lower part of the fire-box, and

fuel feeding means delivering fine fuel into the space under the arch and above the twyer, said twyer discharging upwardly across the path of the feed of the fine fuel and thereby maintaining this fuel in suspension below the arch while being burned.

In testimony that I claim the same to be

my own I have hereunto affixed my signature.

JOHN A. WELTON.
